(57) **CLAIM**

What is claimed is the ornamental design for the hand sander, as shown and described herein.

DESCRIPTION

FIG. 1 is a perspective view of a hand sander showing our new design;

FIG. 2 is a top view of a hand sander showing our new design; FIG. 3 is a right side elevation view of a hand sander showing our new design;

FIG. 4 is a left side elevation view of a hand sander showing our new design;

FIG. 5 is a bottom plan view of a hand sander showing our new design;

FIG. 6 is back end view of a hand sander showing our new design; and,

FIG. 7 is front end view of a hand sander showing our new design.

The dotted line in the drawing is intended to represent sandpaper attached to the bottom of the sander and is not part of the claimed design.
